UNITED STATES PATENT OFFICE.

BENJAMIN F. BARNES, OF ROCKFORD, ILLINOIS.

DRILLING-MACHINE.

No. 831,698.

Specification of Letters Patent.

Patented Sept. 25, 1906.

Application filed May 20, 1903. Serial No. 158,054.

To all whom it may concern:

Be it known that I, BENJAMIN F. BARNES, a citizen of the United States, residing at Rockford, in the county of Winnebago and State of Illinois, have invented certain new and useful Improvements in Drilling-Machines, of which the following is a specification.

This invention relates to drilling-machines, and refers particularly to the mechanism for automatically raising and lowering the drill-spindle. Much time is consumed in the operation of drills of the ordinary construction in advancing the drill from its starting-point to its work and in raising it after its work is done to said starting-point.

The object of this invention is the provision of a mechanism intended to obviate the objection mentioned by fitting a drilling-machine with means for quickly advancing the drill to its work and for quickly returning said drill to its initial or starting position after its work is done.

A further object of the invention is the combination in a drilling-machine of said quick feed with the work-feed.

The invention has for a further object the various improvements in construction hereinafter more fully pointed out.

In the accompanying drawings, Figure 1 is a side elevation of a drilling-machine embodying the features of this invention, showing the parts in their starting or initial position. The lower part of the supporting-column and the work-table are not represented, as the invention does not refer thereto. Fig. 2 is a similar view taken from the opposite side of the machine, the parts being in the same position as in the preceding figure. Fig. 3 is a front elevation of this drilling-machine, the parts being in the same position as in Fig. 1. Fig. 4 is a detail sectional view taken on the axial line of the feed-shaft. Fig. 5 is a transverse sectional view taken through the feed-shaft, showing the worm-wheel and its ratchet connection with said shaft. Fig. 6 is a side elevation of the friction drive-pulley for the quick-feed mechanism. Fig. 7 is a face view of the cam-disk of the quick-feed mechanism in the position it occupies in Fig. 1, showing the fixed stop-pin and the roller-studs of the detent-arm. Fig. 8 is a similar view showing the disk after half

a revolution—that is to say, in the position it occupies after the quick feed has operated to lower the drill-spindle to its work.

In the embodiment herein shown of this invention a drilling-machine is supplied with a work-feed susceptible of the usual changes in speed by means of cone-pulleys and in this instance adapted to be connected with and disconnected from the drill-spindle. A further mechanism is provided to quickly advance the drill to its work and quickly restore the drill to its starting position, which quick-acting feed mechanism is arranged to operate conjointly with said work-feed, but not concurrently therewith—that is to say, the quick feed places the drill in a position adjacent to its work, the work-feed then advances the drill through the work, and finally the quick feed restores the spindle to its starting position.

In the construction of a drilling-machine embodying my invention I provide a main frame 1, comprising the supporting-column 2, the integral upwardly-extending rear arm 3, the upwardly-extending forward arm 4, the connecting-arm 5, the fixed horizontal shaft 6, and the bracket 7, secured at its rear end to the connecting-arm 3 and at its forward end to the fixed shaft 6. A drill-spindle 8 is mounted in the usual manner in the supporting-frame 1 and is provided with a sleeve 9, having an integral rack 10, by means of which said spindle is raised and lowered. A drive-shaft 11 is rotatably mounted in the upper part of the supporting-frame and is connected with the drill-spindle 8 by means of the bevel-gears 12 and 13, the former fixed on the forward end of the drive-shaft and the latter splined upon the drill-spindle. A cone driving-pulley 14 and a cone feed-pulley 15 are fixed upon the drive-shaft 11. The drill-spindle is counterbalanced by a weight (not shown) connected with said spindle by means of the chain 16, and said spindle is raised and lowered by a pinion 17, fixed upon the feed-shaft 18, which pinion meshes with the teeth of the rack 10. The feed-shaft 18 is supported in suitable bearings in the main frame, and its outer end is connected with the fixed shaft 6 of the main frame by means of a brace-arm 19. Between said brace-arm and the pinion 17, the feed-shaft 18 carries a spider 20, having radial openings 21 for receiving a lever (not

shown) for raising and lowering the spindle by hand. The feed-shaft also carries a ratchet-wheel 22, fixed to said shaft, and adjacent to the ratchet-wheel a worm-wheel 23, loosely mounted on the shaft, but engaging with the ratchet-wheel by means of pawls 24, pivotally mounted upon the side of the worm-wheel and held in contact with the teeth of the ratchet-wheel by means of the springs 25.

10 The opposite end of the feed-shaft 18 carries a pinion 26, fixed thereon.

The work-feed will first be described. A shaft 27 is rotatably mounted in suitable bearings in the bracket 7 of the main frame and carries a cone-pulley 28, coinciding with the similar cone-pulley 15, fixed upon the drive-shaft, said pulleys being rotatably connected by means of a drive-belt 29. The forward end of the shaft 27 carries a bevel-pinion 30, adapted to mesh with the teeth of a bevel-gear 31, fixed on a shaft 32, rotatably mounted in a swinging yoke 33, which yoke is supported upon the fixed shaft 6 of the main frame. The lower end of the shaft 32 carries a worm 34, adapted to mesh with the worm-wheel 23 of the feed-shaft. To shift the worm 34 into and out of engagement with the worm-wheel 23, the lower end of the yoke 33 is provided with an oblique elongated opening 35, through which extends a stud 36, fixed to an operating-lever 37, which lever is pivotally supported upon the stud 38, secured to the main frame. The forward end of the operating-lever terminates in the handle 39, and the rear end carries a roller 40, adapted to engage the conical point of a spring-plunger 41, which plunger tends to hold the operating-lever at either extremity of its oscillatory movement. When the operating-lever is raised, the worm 34 is thrown into engagement with the worm-wheel 23, and the feed-shaft 18 will be rotated by the work-feed.

The quick feed will next be described. A shaft 42 is supported in suitable bearings in the main frame and carries at its rear end a spider 43, fixed on said shaft, which spider is provided with radial arms 44, carrying at their outer ends friction-shoes 45, having a facing 46, of leather or other suitable material. These friction-shoes are held by means of the coil-springs 46^a outward against the finished inner surface of a drive-pulley 47, loosely mounted upon said shaft 42, and have a constant frictional engagement with said pulley. The forward end of the shaft 42 carries a bevel-pinion 48, which pinion meshes with the teeth of a bevel-gear 49, fixed upon one end of a short transverse shaft 50, rotatably mounted in a suitable bearing in the upper part of the main frame. The opposite end of the shaft 50 carries a cam-disk 51, having a rim 52 projecting from the face thereof. The rim 52 is annular save for a notch 53, cut therefrom, and an inwardly-extending cam portion 54 adjacent to said notch. The notch forms a stop-shoulder 53^a, the function of which and of the inclined cam portion 54 will appear hereinafter. At a point diametrically opposite the notch 53 the rim 52 is provided with a stud 55. A detent-arm 56 is pivotally supported upon the main frame at a point adjacent to the cam-disk and carries near its forward end two roller-studs 57 and 58, adapted to lie upon opposite sides of the rim 52. At a point between these roller-studs the detent-arm is provided with a stop-pin 58^a, adapted to lie in the path of and be engaged by the stud 55 on said rim. The detent-arm 56 is connected with the operating-lever 37 by means of the pivotal link 59 and is moved with said lever by reason of such connection. The bevel-gear 49 carries upon its outer face a wrist-pin 60, upon which wrist-pin is mounted a screw-threaded rod 61, carrying correspondingly screw-threaded adjusting-collars 62 and 63 and locking-collars 62^a and 63^a. Intermediate said collars 62 and 63 the screw-threaded rod extends through a sleeve 64, which sleeve is pivotally connected with a gear-sector arm 65, affording by an adjustment of said collars on the rod a limited sliding or lost-motion connection between the rod and the gear-sector arm. This gear-sector arm is pivotally mounted upon the supporting-frame by means of the stud 66, and its gear-teeth mesh with those of a pinion 67, which pinion is rotatably mounted upon a stud 68, carried by the main frame, and is affixed to an adjacent pinion 69, which latter pinion meshes with the pinion 26 upon the feed-shaft 18. The sector-arm is provided with an upwardly-extending projection 70, having three openings 71, any one of which openings is adapted to receive the rear end of a tripping-rod 72, the forward end of which carries a movable dog 73, susceptible of being fixed to said rod at any point in its length by means of a set-screw 74. At its forward end the tripping-rod 72 extends through a loop 75 in an arm 76, secured to the oscillatory transverse shaft 77, rotatably mounted in the bearing 78 in the main frame. The opposite end of this shaft carries a crank-arm 79, having at its outer end a roller-stud 80, adapted to engage the upper edge of the operating-lever 37 and to depress said lever when the tripping-rod is reciprocated.

The friction-pulley 47 is constantly rotated by means of a drive-belt 81; but the shaft 42 is normally held stationary against the frictional rotative tendency of said pulley by means of the detent-arm 56 engaging portions of the cam-disk 51. Whenever the detent-arm is withdrawn, the cam-disk 51 and its shaft, being released to the rotative tendency of the friction-pulley 47, make half a revolution, and said screw-threaded rod is moved either upward or downward, depend-

ing upon the position of the bevel gear-wheel 49.

Assuming the parts to be in the position indicated in Figs. 1, 2, and 3 of the drawings, and further supposing that motion is being imparted to the drive-shaft 11 and to the friction-pulley 47 by suitable belts, the machine may be thrown into operation by raising the handle 39 of the operating-lever 37 sufficiently to move the stop-pin 58^a on the detent-arm 56 from out the path of the stud 55 on the cam-rim 52, releasing the quick-feed mechanism to action. This movement of the operating-lever 37 to start the quick feed is not sufficient to throw the work-feed into action. The bevel-gear 49 is now rotated by the friction-pulley 47 and the screw-threaded rod 61 moved downward. As soon as the collar 62 is brought by this downward movement of the rod 61 into contact with the upper face of the sleeve 64 the sector-lever 65 is oscillated, and by means of the gear connection between said sector-lever and the feed-shaft 18 said feed-shaft is rotated to lower the drill-spindle. As the cam-disk 51 is rotated the inclined cam portion 54 of the rim 52 is brought into engagement with the roller-stud 57, raising the detent-arm 56 and with it the operating-lever 37, thereby throwing the worm 34 into engagement with the worm-wheel 23, and thus connecting the feed-shaft 18 with the work-feed. The continued rotative movement of the cam-disk brings the stop-shoulder 53^a of the cam-rim 52 into engagement with the roller-stud 58, stopping the rotative movement of the cam-disk 51 and causing the friction-shoes 45 again to slip with relation to the friction-wheel 47. The drill-spindle now descends under the action of the work-feed, moving the gear-sector downward slowly, and thereby pushing the tripping-rod forward until the dog 73 on said tripping-rod engages the arm 76 and moves it forward. The forward movement of the arm 76 oscillates the shaft 77, to which said arm is fixed, moving the crank-arm 79, also secured to said arm, and thereby depresses the operating-lever 37. This depression of the operating-lever carries the roller 40 to the opposite side of the tip of the spring-plunger 41, whereupon said plunger still further depresses the lever 37 and disconnects the work-feed from the feed-shaft 18 by oscillating the yoke 33, thus throwing the worm 34 out of engagement with the worm-wheel 23. It also removes the roller-stud 58 from engagement with the stop-shoulder 53^a of the cam-disk 51, again releasing the quick feed to action. The friction-pulley 47 through its supporting-shaft 42 now rotates the bevel-gear 49 and raises the screw-threaded rod 61. When the collar 63 on the screw-threaded rod 61 is brought into engagement with the under face 65 of the sleeve 64, the gear-sector arm 65 is

swung upward, rotating the feed-shaft 18 and raising the drill-spindle into its starting position. When the wrist-pin 60 reaches its uppermost position, the stop-pin 55 on the cam-rim 52 has been brought by the rotation 70 of the cam-disk 51 into engagement with the stop-pin 58^a on the detent-arm 56, again stopping the movement of the quick feed. The mechanism has now completed its cycle of movement and is in a position to be again 75 started by raising the handle 39 of the operating-lever 37. It will be understood that the collars 62 and 63 are adjusted upon the screw-threaded rod 61 to determine the relation between the extent of "lost motion" 80 and effective movement between the screw-threaded rod 61 and the gear-sector 65. By this means the drill may be raised to any desired height within the limits of the drilling-machine above its work, and all or any portion of its vertical movement may be divided 85 in any ratio desired between the work-feed and the quick-advance feed. By removing the stop-pin 55 from the rim of the cam-wheel the action of the mechanism may be made 90 continuous, the cycle of movement hereinbefore described being constantly and indefinitely repeated. The dog 73 is adjusted upon the tripping-rod 72 to determine the point at which the downward movement of 95 the drill-spindle under the control of the work-feed shall cease and the upward movement of said spindle under the action of the quick feed shall begin, and the rate of the longitudinal movement of said tripping-rod 100 72 is alterable by changing it from one to another of the openings 71. To adjust the mechanism to a certain piece of work, the collar 63 is moved to such a position on the screw-threaded rod 61 that the drill will be 105 raised by the quick-feed mechanism to a sufficient height above the work to amply clear it. The collar 62 is then moved on the rod to such position that when the rod is in its lowermost position the drill will be placed by the 110 oscillation of the gear-sector arm 65 immediately above its work, and the dog 73 is located on the tripping-rod 72, so that the crank-arm 79 will depress the operating-lever 37 immediately after the drill emerges 115 through its work. The collars 62 and 63 are locked in these positions by means of their locking-collars 62^a and 63^a, and the dog 73 is set in its position by means of the set-screw 74. While the screw-threaded rod 61 always moves the same distance vertically, any desired portion of its movement may be "lost" in its connection with the sector-arm 65 and the drill-spindle moved downward to its work by the quick feed any distance desirable and restored by said feed to any starting position that may have been selected. The yielding connection between the work-feed and the feed-shaft 18, which in this instance has been made in the form of a ratchet 120 125 130

and pawls, permits an overlapping in the application of the work-feed and the quick feed—that is to say, the work-feed may be thrown into action a little before the quick feed ceases to act upon the feed-shaft. If some yielding connection between the feed-shaft and one or the other of these feeds was not provided, breakage would result, as it would be practically impossible to throw the work-feed into action at the very instant the quick feed ceased to act upon the feed-shaft. It is apparent that a yielding spring device might be employed and likewise that various forms of ratchets and ratchet-clutches would answer the purpose.

It is obvious that many changes and modifications might be made in the quick-feed mechanism without departing from the spirit and scope of my invention, also that the quick-advance movement of the spindle might be eliminated and the quick-return movement retained, in view of all of which I desire to have it understood that I do not limit myself to the embodiment herein shown of my invention, but claim said invention broadly.

I claim as my invention—

1. In a drilling-machine, in combination, a drill-spindle; means for advancing said spindle under one feed speed; means for advancing said spindle under a different feed speed; and means actuated by one of said advancing means for changing the advance of said spindle from one feed speed to the other.
2. In a drilling-machine, in combination, a drill-spindle; means for advancing said spindle under one feed speed; means for advancing said spindle under a different feed speed; means for successively placing said advancing means in operative connection with said spindle; and means actuated by one of said advancing means for operating said last-mentioned means.
3. In a drilling-machine, in combination, a drill-spindle; means for advancing said spindle under one feed speed; means for advancing said spindle under a different feed speed; means for successively placing said advancing means in operative connection with said spindle; means actuated by one of said advancing means for operating said last-mentioned means; and a yielding connection between said spindle and the slower one of said advancing means.
4. In a drilling-machine, in combination, a drill-spindle; a work-feed mechanism and a quick-advance-feed mechanism for the spindle, said work-feed mechanism having a yielding connection with said spindle; means for successively placing said feeds in connection with said spindle; and means automatically actuated for operating said last-mentioned means.
5. In a drilling-machine, in combination, a drill-spindle; a work-feed mechanism and a

quick-advance-feed mechanism for the spindle, said work-feed mechanism having a yielding connection with said spindle; means for successively placing said feeds in connection with said spindle; means automatically actuated for operating said last-mentioned means; and means for varying the extent of the advance movement of the spindle under one of said feeds.

6. In a drilling-machine, in combination, a drill-spindle; a feed-shaft for said spindle; two gears on said feed-shaft, one of said gears having a ratchet connection with said shaft; a work-feed adapted to engage with said ratchet-gear; a quick-advance feed adapted to mesh with the other one of said gears; means for successively placing said feeds in connection with said spindle; and means automatically actuated for operating said last-mentioned means.

7. In a drilling-machine, in combination, a drill-spindle; a work-feed and a quick feed for successively advancing the spindle; and means for varying the extent of the advance movement of the spindle under the work-feed; said quick feed comprising means for throwing the work-feed into action.

8. In a drilling-machine, in combination, a drill-spindle; a work-feed and a quick advance and return feed for said spindle said feeds operating successively; means adapted to be actuated by the quick-advance feed for starting the work-feed; and means adapted to be actuated by the work-feed for starting the quick-return feed.

9. In a drilling-machine, in combination, a drill-spindle; a work-feed and a quick advance and return feed for said spindle said feeds operating successively; means for actuating said quick feed; a detent for holding said quick feed from action, said quick feed comprising means for throwing the work-feed into action, and means for releasing said detent.

10. In a drilling-machine, in combination, a drill-spindle; a work-feed and a quick advance and return feed for said spindle said feeds operating successively; a friction driving means for actuating said quick feed; means for holding said quick feed from action; and means for releasing said quick feed to action, said quick feed comprising means for throwing the work-feed into action.

11. In a drilling-machine, in combination, a drill-spindle; a work-feed and a quick advance and return feed for said spindle, said feeds operating successively; means for placing either of said feeds in connection with said spindle; and means adapted to be actuated by the quick feed for operating said last-mentioned means to change from the quick-advance to the work feed and to disconnect the quick return feed.

12. In a drilling-machine, in combination, a drill-spindle; a work-feed and a quick ad-

vance and return feed for said spindle; said feeds operating successively; means for placing either of said feeds in connection with said spindle; means adapted to be actuated by the quick feed for operating said last-mentioned means; and means operated by the work-feed for actuating said means for placing said feeds in connection with the spindle.

13. In a drilling-machine, in combination, a drill-spindle; a work-feed and a quick advance and return feed for said spindle; said feeds operating successively; means for actuating the quick feed to lower the spindle; means adapted to be actuated by the quick feed for connecting the work-feed with the spindle; and means adapted to be actuated by the advance movement of the spindle under the work-feed for placing the spindle in operative connection with the quick feed to raise said spindle.

14. In a drilling-machine, in combination, a drill-spindle; and a quick advance and return feed for said spindle, said quick feed comprising a driving means, a screw-threaded rod adapted to be reciprocated thereby, an oscillatory lever loosely connected with said rod, and nuts on said rod for adjustably limiting the extent of movement of said rod with reference to said lever.

15. In a drilling-machine, in combination, a drill-spindle; a work-feed and a quick advance and return feed for said spindle, said quick feed comprising a friction driving means, a detent for holding said driving means from action, a rod adapted to be reciprocated by the driving means, an oscillatory gear-sector having a sliding connection with said reciprocating rod, means for limiting the extent of movement of the rod with relation to the sector, a driving connection between the sector and the drill-spindle to raise and lower said spindle, a shifting-lever for throwing the work-feed into connection with the spindle, a cam movable synchronously with the reciprocating rod for operating the shifting-lever to connect the work-feed with the drill-spindle, an arm movable with the gear-sector for operating the shifting-lever to disconnect the work-feed from the drill-spindle and to release the quick feed to the action of its friction driving means to raise the spindle.

16. In a drilling-machine, in combination, a drill-spindle; a quick advance and return feed for said spindle; said quick feed comprising a driving means, a rod adapted to be reciprocated thereby, an oscillatory lever having a guide-sleeve for said rod, and adjustable stops on the rod for engaging said guide-sleeve to limit the extent of movement of the rod with relation to the lever.

17. In a drilling-machine, in combination, a drill-spindle; a quick advance and return feed for said spindle, said quick feed comprising

ing a friction driving means, a screw-threaded rod adapted to be reciprocated thereby, a detent for holding said driving means from action, an oscillatory lever, said rod having a sliding connection with said lever, nuts on said rod for adjustably limiting the extent of movement of the rod with relation to the lever, and means for withdrawing said detent.

18. In a drilling-machine, in combination, a drill-spindle; a work-feed and a quick advance and return feed for said spindle, said quick feed comprising a friction driving means, a rod adapted to be reciprocated thereby, a detent for holding said driving means from action, an oscillatory lever, said rod having a sliding connection with said lever, means for adjustably limiting the extent of movement of the rod with relation to the lever, a shifting-lever connected with said detent for connecting the work-feed with the spindle, and means for withdrawing said detent and operating said shifting-lever.

19. In a drilling-machine, in combination, a drill-spindle; a work-feed and a quick advance and return feed for said spindle, said quick feed comprising a friction driving means, a rod adapted to be reciprocated thereby, a detent for holding said driving means from action, an oscillatory lever, said rod having a sliding connection with said lever, means for limiting the extent of movement of the rod with relation to the lever, a shifting-lever connected with said detent for connecting and disconnecting the work-feed with the spindle, means for withdrawing said detent and operating said shifting-lever, and means adapted to be operated by the advance movement of the spindle for operating said shifting-lever to disconnect the work-feed from the spindle and to release the quick feed to action to raise the spindle.

20. In a drilling-machine, in combination, a drill-spindle; a work-feed and a quick advance and return feed for said spindle, said quick feed comprising a friction driving means, a rod adapted to be reciprocated thereby, an oscillatory lever loosely connected with said rod, means for limiting the extent of movement of said rod with reference to said lever, a shifting-lever for connecting the work-feed with the drill-spindle, a detent to prevent the reciprocation of said rod, means for operating said detent, means moving synchronously with said rod for operating said shifting-lever to connect the work-feed with the spindle, and means moving with said oscillatory lever for operating said shifting-lever to disconnect the work-feed from the spindle and to permit the operation of the friction driving means to raise the spindle.

21. In a drilling-machine, in combination, a drill-spindle; a work-feed and a quick advance and return feed for said spindle, said quick feed comprising a driving means, a rod adapted to be reciprocated thereby, an oscil-

latory gear-sector having a sliding connection with said reciprocatory rod, means for adjustably limiting the extent of movement of the rod with relation to the sector, and a gear connection between the sector and the drill-spindle to raise and lower said spindle; and means for successively placing said feeds in action.

22. In a drilling-machine, in combination, 10 a drill-spindle; a work-feed and a quick advance and return feed for said spindle, said quick feed comprising a driving means, a means for withholding said driving means from action, a shifting-lever for throwing the work-feed into connection with the spindle, 15 means operated by the quick feed for actuating said shifting-lever to connect the work-feed with the drill-spindle, means actuated by the work-feed to operate said shifting-lever to throw the work-feed out of engagement with the drill-spindle and to permit the 20 operation of the quick feed to raise the drill-spindle.

23. In a drilling-machine, in combination, 25 a drill-spindle; a feed-shaft therefor; a quick-return feed having a driving connection with said feed-shaft; a work-feed; a shifting-lever for connecting said work-feed with and disconnecting it from the feed-shaft; 30 a friction driving means for said quick-return feed; a detent for holding said driving means from action, said shifting-lever and said detent being connected to operate simultaneously; and a device adapted to be moved by the rotation of the feed-shaft under the operation 35 of the work-feed to actuate said shifting-lever to disconnect the work-feed from said feed-shaft and to withdraw said detent to permit the operation of the quick-return feed to raise the drill-spindle.

24. In a drilling-machine, in combination, 40 a drill-spindle; a feed-shaft; a work-feed and a quick-return feed for said spindle; said quick feed having a gear connection with said feed-shaft; a worm-wheel loosely mounted on said feed-shaft but having a ratchet connection therewith; a worm forming a part of the work-feed; a friction driving means for said quick-return feed; a detent for holding said 45 quick feed from action; a shifting-lever for moving said worm into and out of engagement with the worm-wheel, which detent and shifting-lever are connected to operate simultaneously; and a device adapted to be actuated by the advance movement of the spindle 50 under the work-feed for operating said shifting-lever to withdraw the worm from engagement with its worm-wheel, also to withdraw said detent to permit the quick-return feed to 55 raise the spindle.

25. In a drilling-machine, in combination, 60 a drill-spindle; a feed-shaft therefor; a work-feed for said spindle; a worm-wheel loosely mounted on said feed-shaft but having a ratchet connection therewith. said work-feed

comprising a worm adapted to mesh with said worm-wheel; a quick-return feed for said spindle having a driving connection with said feed-shaft; a friction driving means for said quick-return feed; a detent for holding said driving means from action; a shifting-lever for moving the worm into and out of engagement with the worm-wheel, said shifting-lever and said detent being connected to move simultaneously; and a device actuated by the 70 movement of the drill-spindle under the work-feed for operating said shifting-lever to withdraw said worm from engagement with the worm-wheel, and the detent from the friction driving means.

26. In a drilling-machine, in combination, 75 a drill-spindle; a feed-shaft therefor; a work-feed for said spindle; a worm-wheel loosely mounted on said feed-shaft but having a ratchet connection therewith, said work-feed comprising a worm adapted to mesh with said worm-wheel; a quick-return feed for said spindle having a driving connection with said feed-shaft; a friction driving means for said quick-return feed; a detent for holding said 80 driving means from action; means for adjustably limiting the effective action of said quick-return feed on the drill-spindle; a shifting-lever for moving the worm into and out of engagement with the worm-wheel; and an 85 arm adapted to be moved by the rotation of the feed-shaft under the action of the work-feed for actuating said shifting-lever to withdraw said worm from engagement with the worm-wheel and said detent from the friction driving means.

27. In a drilling-machine, in combination, 90 a drill-spindle; a feed-shaft therefor; a gear having a slip connection with said feed-shaft, said gear forming part of a-spindle-feed mechanism; a second faster spindle-feed mechanism operatively connected with said feed-shaft; and automatic means for breaking the gear connection of which said gear is a part.

28. In a drilling-machine, in combination, 95 a drill-spindle; a feed-shaft therefor; a quick-feed mechanism having a driving connection with said feed-shaft; a gear having a slip connection with said feed-shaft; a work-feed mechanism comprising a movably-supported shaft and a gear on said movably-supported shaft adapted to mesh with the gear on said feed-shaft; and means whereby said movably-supported shaft is moved to separate said gears.

29. In a drilling-machine, in combination, 100 a drill-spindle; a feed-shaft therefor; a quick-feed mechanism having a driving connection with said feed-shaft; a gear having a slip connection with said feed-shaft; a pivotally-mounted shaft carrying a gear adapted to mesh with said first-mentioned gear; means for rotating said pivoted shaft; and means whereby said pivoted shaft is pivotally moved to separate said gears.

30. In a drilling-machine, in combination, a drill-spindle; a feed-shaft therefor; a quick-feed mechanism geared to said feed-shaft; a worm-wheel having a slip connection with said feed-shaft; a work-feed mechanism comprising a pivotally-supported shaft carrying a worm adapted to mesh with the worm-wheel on said feed-shaft; and automatic means whereby said pivotally-supported shaft is moved to separate said worm and worm-wheel.

BENJAMIN F. BARNES.
